UNITED STATES PATENT OFFICE.

LEVI D. VAN VALKENBURG, OF HOLYOKE, MASSACHUSETTS, ASSIGNOR OF ONE-HALF TO JOSEPH M. DUNHAM, OF SAME PLACE.

BOBBIN-SUPPORT FOR SPINNING-SPINDLES.

SPECIFICATION forming part of Letters Patent No. 398,809, dated February 26, 1889.

Application filed October 18, 1887. Serial No. 252,761. (No model.)

To all whom it may concern:

Be it known that I, LEVI D. VAN VALKENBURG, a citizen of the United States, residing in Holyoke, in the county of Hampden, State 5 of Massachusetts, have invented a certain new and useful Improvement in Bobbin-Supports for Spinning-Spindles, of which the following is a description sufficiently full, clear, and exact to enable any person skilled in the 10 art to which said invention appertains to make and use the same, reference being had to the accompanying drawings, forming a part of this specification, in which—

Figure 1 shows a portion of a spindle and 15 a sectional view of my improved button or bobbin-support and check-nut thereon; Fig. 2, a side elevation of the same, the entire spindle being shown; and Fig. 3, a plan of the button or bobbin-support and check-nut.

Like letters of reference indicate corresponding parts in the different figures of the 20 drawings.

My invention relates more especially to spindles employed on spinning-frames and 25 twisters; and it consists of an improved button or bobbin-support for said spindles and check-nut for the same, whereby said check-nut prevents said button from unscrewing and slipping on the spindle.

The nature and operation of the improvement will be readily understood by those conversant with such matters from the following 30 explanation.

In the drawings, A represents the button 35 or bobbin-support, B the check-nut, and E the spindle proper. The button A is interiorly threaded at its lower end, as shown in Fig. 1, and chambered on its upper side, as shown at G, to receive the check-nut B. The 40 spindle E is exteriorly threaded at C, to correspond with the interior threads of button A and check-nut B. The button A is screwed down onto the shoulder F of the spindle E, and the check-nut B is screwed down firmly 45 onto the bottom of the chamber G by means of a suitable implement inserted in the slots H at the top of said check-nut. The button A is provided with pins or lugs D, which enter the bottom or under side of a bobbin, said 50 bobbin being provided with holes or other suitable means on its under side, adapted to receive the pins or lugs D on the button A,

which prevents said bobbin from slipping on the button.

As spindles of this character are intended 55 to rotate in only one direction—either to the right or to the left—the screw-threads on the spindles, and within the buttons or bobbin-supports, are made either right or left hand, according to the direction in which the spindles 60 are intended to rotate, whereby the sudden stopping of the spindle by taking hold of the bobbin, which is often done, would tighten the button or bobbin-support on the shoulder of the spindle, and by reversing the rotation 65 of the spindle the aforesaid manner of stopping the spindle would loosen instead of tighten the button on the shoulder of the spindle; and as it occasionally becomes necessary to reverse the rotation of the spindles 70 or cause them to rotate in an opposite direction from that in which they were intended much difficulty is then experienced, owing to the unscrewing and slipping of the buttons or bobbin-supports on the spindles, which de- 75 prives the yarn or thread of its required twists.

My invention is designed to overcome this and other objections and difficulties; and to that end I make use of the means described 80 whereby the buttons or bobbin-supports are firmly held in position on the spindles by means of the check-nuts B, and may rotate either to the right or to the left without unscrewing and slipping on the spindles. 85

Having thus explained my invention, what I claim is—

1. The combination, with the screw-threaded spindle, of the interiorly-threaded button or bobbin-support A and the interiorly-threaded 90 check-nut B, said button being chambered on its upper side to receive the check-nut, substantially as described.

2. The combination, with the screw-threaded spindle, of the interiorly-threaded button A, 95 chambered at G and provided with the pins or lugs D, and the check-nut B, formed with the slots H, substantially as described.

October 12, 1887.

LEVI D. VAN VALKENBURG.
